UNITED STATES PATENT OFFICE.

EDWARD STAELHLI, OF LA GRANGE, ILLINOIS.

PENDANT SETTING MECHANISM.

1,407,231.

Specification of Letters Patent. Patented Feb. 21, 1922.

Application filed January 17, 1921. Serial No. 437,795.

To all whom it may concern:

Be it known that I, EDWARD STAELHLI, a citizen of the United States, residing at La Grange, in the county of Cook and State 5 of Illinois, have invented a certain new and useful Improvement in Pendant Setting Mechanism, of which the following is a full, clear, concise, and exact description, reference being had to the accompanying drawings, forming a part of this specification.

My invention relates to pendant setting mechanism for watches and has to do more particularly with an improved and simplified mechanism for operating the clutch 15 wheel by the winding and setting stem, and also for holding the stem in operative relation to the winding and setting mechanism in such a manner that it may be readily removed therefrom.

Mechanism of this character, and particularly where used in the very small watches such as wrist watches and the like, the parts ordinarily are of very minute construction and so closely mounted on account 25 of lack of space that some of the screws and levers are so minute and mounted so close to edges of the plates that it is exceedingly difficult to assemble and disassemble the parts.

One of the features of my invention is the provision of a pendant winding and setting mechanism of the positive type in which the elements are sufficiently separated and so mounted that more space is given to the 35 placing of screws and the use of larger ones than ordinarily employed.

Another feature of my invention is the provision of a slidably mounted primary clutch wheel shift bar which is acted upon 40 by the stem to shift the clutch wheel and also acts to hold the stem in the watch.

Another feature is the provision of a cam shouldered screw for holding the slidably mounted primary bar in operative relation 45 to the stem but which screw may be rotated to permit separation of the parts so that the stem may be withdrawn.

There are other features of my invention but these will be more particularly referred 50 to throughout the specification and in the appended claims.

For a better understanding of my invention reference is to be had to the accompanying drawing in which—

Fig. 1 is a face view showing the preferred

form of my improved pendant winding and setting mechanism with the parts in winding position;

Fig. 2 shows the parts with the stem in setting position; 60

Fig. 3 shows the slidably mounted primary clutch wheel shift bar pressed out of operative relation with the stem to permit withdrawal thereof;

Fig. 4 is a transverse section along the 65 line 4—4 of Fig. 3; and

Fig. 5 is an enlarged view of the cam shouldered screw and primary bar or setting cam.

Referring now more in detail to the form 70 of my invention as illustrated, I have shown the main frame 6 of the watch but have left out the usual standard mechanism employed, showing only the parts immediately involved in the winding and setting mechanism. The 75 winding and setting stem 7 is also shown extending downwardly through the usual winding pinion 8 and clutch wheel 9 to a suitable bearing at its lower end. The clutch wheel 9 is slidably carried by the 80 stem 7 and when in its upper position engages the winding pinion 8 but when in its lower position engages the setting pinion 10, which is, of course, connected to the usual gear train to the hands although this 85 is not shown. The pinion 8 and clutch wheel 9 are set in suitable recesses so that they will be maintained in proper alignment when the stem 7 is withdrawn. The clutch wheel 9 has a central annular groove 90 engaged by the arm of the secondary shifting lever 11, this lever being mounted in a recess between the main frame and the usual cover plate or bridge piece depending upon the construction employed. This secondary 95 lever 11 is pivotally mounted by a screw 12 which with my improved construction may be spaced a desirable distance from the edge of the frame so as to provide sufficient stock between the screw and the edge 100 of the frame to make it of more easy construction. Also by means of my improved construction the screw 12 may be made of larger diameter than heretofore employed in setting mechanism of the positive type 105 such as is here employed. This is, of course, of great importance where parts are so closely assembled a few thousandths of an inch is frequently considerable. In order to maintain the secondary lever under tension I 110

provide a spring 13 which acts upon the depending portion of the secondary lever 11 so as to normally hold the clutch wheel 9 in operative engagement with the winding 5 pinion 8.

In order to shift the secondary lever 11 so as to move the clutch wheel 9 from its winding to its setting position and vice versa, I provide a primary setting bar 14 10 slidably mounted upon the frame between the plates of the watch and supported at one end by the pin 15 which extends through a movement limiting slot in the bar 14, and supported at its other end by a screw 16 15 which holds the end 14^a of the primary bar in operative relation to the annular slot 7^a in the stem 7, so that the shifting of the stem will slidably move the primary bar 14. I also provide a spring 17 which engages the 20 primary bar 14 under tension. This spring 17 serves several purposes. One purpose is to act upon the primary bar or setting cam 14 so as to effect a snap action of the stem 7 when moved from one position to another. 25 This is brought about by the free end of the spring 17 engaging the notches in the bar 14 as it is shifted from one position to another. That is, as the movement of the stem 7 and setting cam 14 is started, as the 30 spring rides over the central portion between the notches, it falls into the opposite depression and thus forces the bar 14 one way or the other.

Another purpose of the spring 17 is to 35 move the arm 14^a out of holding engagement with the annular groove 7^a of the stem, as shown in Fig. 3, so as to permit a withdrawal of the stem. In order to bring this about, screw 16 is turned so that its cam-shaped portion 16^a is moved far enough to 40 permit the spring 17 to press the primary bar 14 away from the stem as in Figs. 3 and 5. Spring 17 also holds the bar and stem in alternate positions.

In order to operate the secondary lever 11 45 so as to shift the clutch wheel 9, cooperating cam mechanism on the primary and secondary levers is provided, this being preferably in the form of a cam-shaped end 14^a carried by the primary bar which engages pin 18 carried by the secondary lever 11. Thus, when the stem 7 is moved from its winding position as shown in Fig. 1 to its 50 setting position as shown in Fig. 2, the upward movement of the primary bar 14 causes the cam 14^a to engage the pin 18 and rotate the secondary lever 11 about its axis 12 so as to move its arm downwardly to shift the clutch wheel 9 into engagement with the setting pinion 10 as shown in Fig. 2. A reverse 55 movement of the stem 7, that is downwardly or inwardly, will bring about a reverse movement of the parts so as to shift the clutch wheel back to its winding position as shown 60 in Fig. 1.

What I claim as new and desire to secure by U. S. Letters Patent is:

1. A pendant winding and setting mechanism for watches including a stem, a clutch-wheel carried by the stem, a primary bar operatively engaged by the stem and having a vertical part slidably mounted to one side thereof, a secondary lever for shifting the clutch-wheel, and cam mechanism carried by said bar and lever beyond the vertical part 70 of the bar whereby the operation of the primary bar actuates the secondary lever to shift the clutch-wheel.

2. A pendant winding and setting mechanism for watches including a stem, a clutch-wheel carried by the stem, a slidably mounted primary bar operatively engaged by the stem, means for releasing the primary bar from the stem to permit withdrawal of the stem, a secondary lever for shifting the 80 clutch-wheel, and cam mechanism carried by said bar and lever whereby the operation of the primary bar actuates the secondary lever to shift the clutch-wheel.

3. A pendant winding and setting mechanism for watches including a stem, a clutch-wheel carried by the stem, a slidably mounted primary bar operatively engaged by the stem, screw operated means for holding the primary bar in operative relation to the stem 90 and whereby said means may be operated to release the primary bar from the stem to permit withdrawal of the stem, a secondary lever for shifting the clutch-wheel, and cam mechanism carried by said bar and lever 100 whereby the operation of the primary bar actuates the secondary lever to shift the clutch-wheel.

4. A pendant winding and setting mechanism for watches including a stem, a primary clutch-wheel shift-bar slidably mounted to move parallel with the stem and in operative relation therewith, a spring tending to press the bar out of operative relation to the stem, and an adjustable stop to normally hold the bar and stem in operative relation but movable to permit said spring to move the bar away whereby the stem may be withdrawn.

5. A pendant winding and setting mechanism for watches including a stem, a primary clutch-wheel shift-bar slidably mounted to move parallel with the stem and in operative relation therewith, a spring tending to press the bar out of operative relation to the stem, notches in said bar cooperative with said spring to effect a snap action of the stem, and an adjustable stop to normally hold the bar and stem in operative relation but movable to permit said spring to move the bar away whereby the stem may be withdrawn.

6. A pendant winding and setting mechanism for watches including an annularly grooved stem, a primary clutch-wheel shift- 130

bar operatively related to said stem by the stem groove, and means for limiting the movement of the shift-bar to limit the movement of the stem, and means whereby the 50

5 shift-bar may be moved laterally away from the stem without dismounting same so as to permit withdrawal of the stem.

7. A pendant winding and setting mechanism for watches including an annularly 10 grooved stem, and a primary clutch-wheel shift-bar operatively related to said stem by the stem groove and also holding the stem against withdrawal, and means whereby the shift-bar may be moved laterally away from 15 the stem without dismounting same so as to permit withdrawal of the stem.

8. A pendant winding and setting mechanism for watches including a stem, a main plate and bridge plate, a primary clutch- 20 wheel shift-bar slidably mounted between said plates in operative relation to the stem, and a screw having a cam-shoulder portion positioned between the plates to hold the bar in operative relation to the stem, said 25 screw being operative to release the shift-bar from operative relation to the stem.

9. A pendant winding and setting mechanism for watches including an annularly grooved stem, a primary clutch-wheel shift- 30 bar operatively related to said stem by the stem groove, and means for slidably mounting said bar so as to be slidably movable parallel with the stem but pivotally mounted so as to be tiltable away from the stem to 35 permit withdrawal thereof.

10. A pendant winding and setting mechanism for watches including a stem, a clutch-wheel carried by the stem, a primary bar operatively engaged by the stem and having 40 a vertical part slidably mounted to one side thereof, a secondary lever for shifting the clutch-wheel, and cam mechanism carried by said bar and lever beyond the vertical part of the bar whereby the operation of the primary bar actuates the secondary lever to 45 shift the clutch-wheel, and an adjustable

stop-screw and spring acting to hold primary bar and stem in operative relation but permit separation of the parts whereby the stem may be withdrawn. 50

11. A pendant winding and setting mechanism for watches including a stem, a clutch-wheel carried by the stem, a slidably mounted primary bar operatively engaged by the stem, a secondary lever for shifting the 55 clutch-wheel and in operative relation with the primary bar, an adjustable cam engaging the bar to normally hold it in operative relation with the stem but whereby the bar is released from the stem when the cam is 60 adjusted so as to permit withdrawal of the stem.

12. A pendant winding and setting mechanism for watches including a stem, a clutch-wheel carried by the stem, a slidably mounted primary bar operatively engaged by the stem, a secondary lever for shifting the clutch-wheel and in operative relation with the primary bar, an adjustable cam engaging the bar to normally hold it in operative 65 relation with the stem but whereby the bar is released from the stem when the cam is adjusted so as to permit withdrawal of the stem, and a spring pressing said bar against the cam. 70

13. A pendant winding and setting mechanism for watches including a stem, a primary clutch-wheel shaft-bar slidably mounted to move parallel with the stem and in operative relation therewith, a spring tending 80 to press the bar out of operative relation to the stem, means on said bar cooperative with said spring to effect a snap action of the stem, and an adjustable stop to normally hold the bar and stem in operative relation 85 but movable to permit said spring to pivotally move the bar away whereby the stem may be withdrawn. 75

In witness whereof, I hereunto subscribe my name this 31st day of December A. D., 90 1920.

EDWARD STAEHLI.
